UNITED STATES PATENT OFFICE

CLARENCE T. DAVIS, OF WORCESTER, MASSACHUSETTS, ASSIGNOR TO ROYAL
WORCESTER CORSET COMPANY, A CORPORATION OF MASSACHUSETTS

MATERNITY CORSET

Application filed November 13, 1930. Serial No. 495,448.

This invention relates to a maternity corset, and has for its object to provide a front which is elastically extensible both vertically and horizontally, so that it will accommodate itself to the changing form of the wearer. To this end the central part of the corset front comprises a series of pleats extending from the top of the front nearly to the bottom thereof, and overlying these pleats and tacked to the folds thereof by stitches is a wide strip of elastic fabric which is stitched to the top of the corset front and also stitched at its lower end to an elastic abdominal supporting belt section. The pleats of the central pleated section are stitched at their ends to sections of elastic fabric, and, owing to the construction just described, the corset front will be elastically extensible both vertically and horizontally.

In the accompanying drawings Fig. 1 is a front view of a belt corset embodying the present invention, and Fig. 2 a front view of a brassière corset also embodying the present invention.

Referring to the drawings, the back 12 of the corset may be of any well known or suitable construction. The front of the corset is preferably connected to the back 12 by lacings 13 which may be loosened or tightened as may be desired. The corset front comprises a narrow vertical strip 14 at one side of the front, connected by the lacings referred to to the back, and which latter may be provided at one edge with a series of eyes 15 to be engaged by hooks at one edge of the corset front, thus affording a side-opening garment.

In the form of the invention herein shown the front consists of non-elastic side sections 17 and 18, a central section 19 comprising a series of horizontally extending pleats. Overlying said pleats is, in this instance, a broad vertical strip 20 of elastic fabric stitched at its upper end to the top of the pleated section and stitched at its lower end to an abdominal supporting belt section comprising side elastic fabric sections 21, and a central elastic section 22, said belt elastic sections 21 and 22 being connected by non-elastic sections 23. The elastic strip

20 is attached to the folds of the pleats at its outer edges by tacking stitches 24, and the pleated section 19 is stitched at its edges to vertical strips 25 of elastic fabric. Instead of the single broad elastic strip 20, as herein shown, a plurality of elastic strips may, if desired, be used in connection with the pleated section.

From the foregoing it will be understood that the corset front is elastically extensible vertically, by virtue of the central elastic fabric strip 20 attached to the folds of the pleated section 19, the loose pleats accommodating themselves to any stretching of the said elastic strip 20. The front is also elastically extensible horizontally by virtue of the elastic strips 25, to which the pleated section 19 is stitched.

This improved corset may be provided at its top with a brassière 26, which is stitched at one edge to the back of the corset and which comprises a broad vertical strip 27 of elastic fabric, so that the brassière is elastically extensible horizontally.

Having thus described my invention I claim and desire to secure by Letters Patent:

1. A corset comprising a central front part consisting of a series of pleats, a strip of elastic fabric overlying said pleats and tacked thereto, said strip being stitched at its top to the pleated section, and an elastic abdominal supporting belt section, below the pleated section, to which the lower end of said overlying elastic strip is stitched.

2. A corset comprising a central pleated front section, and a strip of elastic fabric tacked to the pleats of said pleated section, thus rendering said front elastically extensible vertically, and strips of elastic fabric at the outer sides of said pleated section, thus rendering said front elastically extensible horizontally.

3. A corset comprising a central pleated front section, and a strip of elastic fabric tacked to the pleats of said pleated section, thus rendering said front elastically extensible vertically, strips of elastic fabric at the outer sides of said pleated section, thus rendering said front elastically

extensible horizontally, said elastic strip being attached at its top to said pleated section, and an elastic abdominal supporting belt section to which said elastic strip is attached.

4. A corset comprising a central front part consisting of a series of pleats, a strip of elastic fabric over-lying said pleats and tacked to the folds thereof, said strip being attached at its top to the pleated section, strips of elastic fabric at each side of said pleated section and connected to said pleats, by stitching, and an elastic abdominal supporting belt section, below said pleated section, to which the lower end of said elastic strip is attached.

5. A corset comprising a central front part consisting of a series of horizontally extending pleats, and a vertical strip of elastic fabric overlying and attached at its edges to said pleats.

6. A corset comprising a central front part consisting of a series of horizontally extended pleats, and a vertically disposed strip of elastic fabric overlying and attached at its edges to said pleats, said corset also comprising a brassière part which is elastically extensible horizontally.

In testimony whereof I affix my signature.
CLARENCE T. DAVIS.
